UNITED STATES PATENT OFFICE

124,905

DESIGN FOR A PORTABLE MIXING MACHINE

Rollin R. Parks, Port Washington, Wis., assignor
to Kwik Mix Concrete Mixer Company, Port
Washington, Wis.

Application March 25, 1940, Serial No. 91,229

Term of patent 14 years

To all whom it may concern:

Be it known that I, Rollin R. Parks, a citizen of the United States, resident of Port Washington, in the county of Ozaukee and State of Wisconsin, have invented a new, original, and ornamental Design for a Portable Mixing Machine, of which the following is a specification, reference being had to the accompanying drawing, forming a part thereof, in which:

Figure 1 is a perspective view of a portable mixing machine showing my new design looking toward the discharging side of the machine.

Figure 2 is a perspective view of the portable mixing machine shown in Figure 1, taken from the other side thereof, and looking toward the charging end thereof.

Figure 3 is a side elevational view of the portable mixing machine shown in Figure 1.

I claim:

The ornamental design for a portable mixing machine, substantially as shown.

ROLLIN R. PARKS.
